FIG. 2

UNITED STATES PATENT OFFICE.

LOUIS B. F. SCHOENFELDT, OF HOLYOKE, MASSACHUSETTS.

DESIGN FOR A TIRE.

59,982.

Specification for Design.

Patented Dec. 13, 1921.

Application filed September 25, 1920. Serial No. 412,881. Term of patent 14 years.

To all whom it may concern:

Be it known that I, LOUIS B. F. SCHOENFELDT, a citizen of the United States of America, residing at Holyoke, in the county of Hampden and State of Massachusetts, have invented a new and original Design for Tires, of which the following is a specification, reference being had to the accompanying drawing, forming part thereof.

Figure 1 is perspective view of the tire, showing my design.

Fig. 2 is an enlarged fragmentary face view of the tire.

I claim:

The ornamental design for a tire as shown.

LOUIS B. F. SCHOENFELDT.
